UNITED STATES PATENT OFFICE.

GEORGE H. GILMAN, OF CLAREMONT, NEW HAMPSHIRE, ASSIGNOR TO SULLIVAN MACHINERY COMPANY, OF BOSTON, MASSACHUSETTS, A CORPORATION OF MASSACHUSETTS.

DRILLING APPARATUS.

1,279,532.

Specification of Letters Patent. Patented Sept. 24, 1918.

Application filed July 19, 1915. Serial No. 40,571.

To all whom it may concern:

Be it known that I, GEORGE H. GILMAN, a citizen of the United States, and a resident of Claremont, county of Sullivan, and State of New Hampshire, have invented an Improvement in Drilling Apparatus, of which the following description, in connection with the accompanying drawings, is a specification, like characters on the drawings representing like parts.

This invention relates to drilling apparatus, and is more particularly though not exclusively concerned with a pressure fluid actuated drilling tool, having pressure fluid feeding means for advancing the tool toward, or retracting it from, its work.

My invention will be best understood by reference to the following specification when taken in connection with the accompanying drawings of one illustrative embodiment thereof, while its scope will be more particularly pointed out in the appended claims.

Figure 1 is a side elevation, partly broken away and partly in section, of a drilling apparatus embodying my invention;

Fig. 2 is a central, vertical, longitudinal section, partly in elevation, of the drilling engine; and

Fig. 3 is a vertical cross section on the line 3—3 of Fig. 1.

Referring to the drawings which show one illustrative embodiment of my invention, I have shown a drilling apparatus having a drilling engine 1, which for purposes of illustration may be substantially identical with the drilling engine illustrated and described in connection with my copending application, Serial No. 21,435, filed April 14, 1915. Cooperating with the drilling engine 1 I prefer to use a drill steel 2 and a drill steel retainer 3. The drilling engine may be attached by any suitable clamp 4, and preferably through an offset member 5, to the feed mechanism. The feed mechanism may comprise a piston 6' having a piston rod 6 and movable in a cylinder 7. In the drawings I have shown the piston rod 6 as operatively attached to the drilling engine, through the offset member 5, while the cylinder 7 is illustrated as attached to a fixed support which preferably includes a fixed clamp 8. Pressure fluid actuated relative movement of the piston rod 6 and the cylinder 7 will result in similar movement of the drilling engine and drill bit relative to the

work. The control of pressure fluid to the drill and to the feeding mechanism is preferably performed by valve mechanism 9 similar to that illustrated and described in the aforesaid copending application 21,435, filed April 14, 1915.

I preferably use drill bit rotating mechanism which may include the ratchet mechanism 10 and is preferably the same or similar to that which forms the subject matter of United States Letters Patent No. 1,034,010, granted to Sullivan Machinery Company, July 30, 1912, as my assignee.

It is of marked advantage to rotate the drill steel, preferably automatically, during the drilling operation. The use of pressure fluid feeding mechanism in connection with such rotation may result in such pressure on the point of the drill steel that rotation of the drill steel may be unduly retarded or even stopped. To prevent this I have found it advantageous to provide means for regulating the force exerted by the feed mechanism on the drill point. While this may be done in a variety of ways without departing from the spirit and scope of my invention, it may take the form of restraining means which, without reducing the power or pressure of the feeding mechanism, does reduce the amount of pressure exerted on the drill point. It is highly desirable that such restraining means be adjustable so that the restraint may be varied according to the nature of the material drilled.

In the specific embodiment of my invention illustrated in the drawings, I accomplish this by means of a friction device comprising a friction member 101 operatively mounted on the feed cylinder 7 and engaging the feed piston rod 6. The gripping effect may be controlled by a bolt 103 preferably cooperating with a manually controllable tensioning and adjusting nut 104, the bolt and nut serving in the illustrative embodiment as means for increasing, decreasing or eliminating altogether the tension of the frictional piston gripping means.

While the before mentioned control is of marked advantage in any construction of rotating, pressure fluid fed drill, it is of particular importance in a drill of the type illustrated wherein the rotation of the drill is actuated by reciprocation of the hammer piston, for it will be readily understood that retarding of the rotary drill, where the

aforesaid hammer piston actuated rotation is used, will result in corresponding retardation and short stroking of the piston, the energy being expended in exerting pressure on the sides of the rifled slot 11 in trying to turn the ratchet member 10 (the details of construction of which are fully described in Patent No. 1,084,010 before mentioned).

Even when used in connection with a rotating mechanism actuated independently of hammer reciprocation, the control of the pressure feed is of great importance for the efficiency of the drill as a whole is greatly impaired by improper functioning of the drill steel rotating apparatus.

I prefer that the drilling engine 1 be so mounted that it may swing away from the drilled aperture so that the drill steel may be readily changed. I may perform this by utilizing my feeding mechanism as a pivot. I prefer that the piston 6 be rotatable in the cylinder 7 and that the piston rod and the drilling engine have substantially parallel axes. The drill bit 2 is preferably alined with the drilling engine 1. Thus when the drilling engine is swung about the pivot it will always remain parallel with the drilled aperture. To hold the drilling engine in any desired lateral position while changing drill steels or when "spotting" holes, I may use any suitable means, but I prefer to use the friction 101 by tightening the nut 104. This, by restraining relative rotation of the piston 6 and cylinder 7, will hold the drilling engine in any desired position about the axis of the feed mechanism.

While I have shown and described one specific embodiment of my invention for illustrative purposes, it is to be understood that my invention is not limited to the specific embodiment shown and described, but that extensive deviations from the illustrative matter may be made without departing from the principle of my invention.

What I claim as my invention and desire to secure by Letters Patent is set forth in the following claims:

1. Drilling apparatus comprising, in combination, a drill cylinder, feeding means including a member fixed relative to the work, a member fixed relative to said cylinder, and pressure fluid actuated means for producing longitudinal feeding movement of the second member whereby said drill cylinder may be advanced relative to the work, an offset member operatively connecting said drill cylinder and said feeding means, said parts providing pivot means whereby said drill cylinder may be swung at right angles to its longitudinal axis to move the same out of alignment with the drill aperture, and friction means controlling said longitudinal feeding movement and said swinging movement.

2. Drilling apparatus comprising, in combination, a drill cylinder, feeding means including a member fixed relative to the work, a member fixed relative to said cylinder, and pressure fluid actuated means for producing longitudinal feeding movement of the second member whereby said drill cylinder may be advanced relative to the work, an offset member operatively connecting said drill cylinder and said feeding means, said parts providing pivot means whereby said drill cylinder may be swung at right angles to its longitudinal axis to move the same out of alignment with the drilled aperture, and friction means controlling said swinging movement.

In testimony whereof, I have signed my name to this specification, in the presence of two subscribing witnesses.

GEORGE H. GILMAN.
